[57] CLAIM

The ornamental design for a magnetic tape reproducer, substantially as shown and described.

DESCRIPTION

FIG. 1 is a front elevation of a magnetic tape reproducer taken at a reduced scale;

FIG. 2 is an enlarged rear perspective view thereof;

FIG. 3 is a top plan view thereof, with the juxtaposed tape reels omitted for clarity of illustration; and

FIG. 4 is a side elevation thereof.

Fig. 1.

Fig. 2.

Fig.3.

Fig.4.
